US00D667509S

(12) **United States Design Patent**
Mimlitch, III et al.

(10) **Patent No.:** **US D667,509 S**
(45) **Date of Patent:** **** Sep. 18, 2012**

(54) **ROBOTIC TOY CAR**

(75) Inventors: **Robert H. Mimlitch, III**, Rowlett, TX (US); **David Anthony Norman**, Greenville, TX (US); **Douglas Michael Galletti**, Allen, TX (US); **Raul Olivera**, Greenville, TX (US); **James Anthony Trzaskos**, Massena, NY (US)

(73) Assignee: **Innovation First, Inc.**, Greenville, TX (US)

(**) Term: **14 Years**

(21) Appl. No.: **29/413,172**

(22) Filed: **Feb. 13, 2012**

(51) LOC (9) Cl. **21-01**

(52) U.S. Cl. **D21/550**

(58) Field of Classification Search ..... D21/533, D21/548, 549, 550, 561, 562, 433; D12/82, D12/86, 88, 89, 90, 91, 92, 93; 446/444-447, 446/452, 465, 468, 470, 471, 431, 454-456; 254/423; 238/10 F

See application file for complete search history.

(57) **CLAIM**

The ornamental design for a robotic toy car, as shown and described.

DESCRIPTION

FIG. 1 is a top perspective view showing a robotic toy car; FIG. 2 is a bottom perspective view of FIG. 1;

FIG. 3 is a top side view of FIG. 1;

FIG. 4 is a bottom side view of FIG. 1;

FIG. 5 is a front side view of FIG. 1;

FIG. 6 is a back side view of FIG. 1;

FIG. 7 is a right side view of FIG. 1; and,

FIG. 8 is a left side view of FIG. 1.

The broken lines are for the purpose of illustrating portions of the environmental structure and forms no part of the claimed embodiment and design.

1 Claim, 7 Drawing Sheets
